Primary Examiner — Kevin K Rudzinski

(57) CLAIM

The ornamental design for a pants decoration, as shown and described.

DESCRIPTION

FIG. 1 is a perspective view of a pants decoration showing my new design;

FIG. 2 is a front view thereof;

FIG. 3 is a rear view thereof;

FIG. 4 is a left side view thereof; and,

FIG. 5 is a right side view thereof.

The broken lines showing a pants decoration are for the purposes of illustrating environment and forms no part of the claimed design.
